HEAT EXCHANGER

Charles H. Stoddard and James Layfield, Wellsville, N.Y., assignors to The Air Preheater Corporation, New York, N.Y., a corporation of New York

Filed Sept. 8, 1959, Ser. No. 838,799
2 Claims. (Cl. 257—267)

This invention relates to a heat exchanger of the class that comprises a mass of heat absorbent element that is adapted to be alternately brought into contact with a stream of heating fluid and a fluid to be heated whereby heat from the heating fluid is transferred to the fluid to be heated through the intermediary of the heat absorbent element. Heat exchangers of this type are known as regenerative heat exchangers, and they are adapted to be either continuously or intermittently exposed to the alternate fluids by flow directing means that includes sealing means arranged to isolate one fluid from the other.

There are today two principal types of regenerative heat exchangers in common use. In one type a regenerative heat absorbent element is rotated between fixed ducts for the heating fluid and the fluid to be heated and in the other type flow directing means at opposite ends of a fixed mass of heat absorbent material are adapted to rotate synchronously whereby the heating fluid and the fluid to be heated are alternately directed through the heat absorbent element.

This invention is directed to the latter type of heat exchanger including a fixed matrix having a pair of flow directing means at opposite ends thereof adapted to rotate in unison to alternately direct the heating fluid and the fluid to be heated through spaced portions of the heat absorbent element. In heat exchangers of this type where the pressure of the heating fluid and the pressure of the fluid to be heated usually vary considerably, difficulty may be encountered in sealing one fluid from another. This invention accordingly attempts to provide an efficient adjusting arrangement for the sealing means that is adapted to preclude leakage of one fluid to the other. Moreover the apparatus of this invention attempts to balance the force of the fluid pressure at opposite ends of the matrix acting against the flow directing means so as to eliminate an inequality of pressure acting upon the spaced flow directing means.

The invention is illustrated by the accompanying drawings that form part of this specification, wherein:

FIGURE 1 is a longitudinal sectional view of a preferred form of our invention.

FIGURE 2 is a transverse sectional view as seen on line 2—2 of FIGURE 1.

Referring more particularly to the drawings, the heat exchanger comprises an outer cylindrical drum 20 and a concentric inner drum 22 that are radially spaced to provide an annular chamber therebetween. The annular chamber is divided by a series of radial partitions or diaphragms 24 to provide a series of sectional compartments 26 therebetween. Each compartment 26 is in turn packed with a mass of regenerative heat exchange material 28 having axial passages therethrough in order that fluid may flow therethrough in a contacting relationship. The outer drum 20 is enclosed in a housing 32 having a pair of ducts 34 and 36 positioned at opposite ends thereof to provide inlet and outlet passages for a low pressure heating fluid. A pair of ducts 39 and 42 are provided with ports to the housing 32 coaxial thereto. These ducts are adapted to direct a high pressure fluid to be heated to and through the axial passages in the mass of heat exchange material 28 carried in the compartments.

A pair of rotatable hood members 44A and 44B that have annular end surfaces 46 remote from the housing 20

2

in sealing relation with the flanged ends 47 of ducts 38 and 42 are adapted to permit substantially leak free rotation of the axially spaced hoods about the vertical axis of the housing. The end of each hood adjacent the housing terminates in a plate 48 adapted to lie in a plane parallel to and adjacent the end face of the mass of heat exchange element. Each plate 48 is centrally apertured at 49 to permit its being mounted on the axial rotor shaft 50. The plates include diametrically spaced apertures 51 adapted to progressively coincide with the several compartments 26 as the hood is rotated about its vertical axis. Sectorial flanges 53 at the side of each aperture 51 are provided to preclude the leakage of fluid out of the chamber within the hood during rotation about its central axis. The hoods 44A and 44B are illustrated as extending diametrically with a pair of apertures 51 available to direct fluid through opposite compartments. Under certain conditions however, it may be desirable to restrict the high pressure fluid to a single side of the heat exchanger and it is entirely within the scope of this invention to utilize a radial hood that directs flow through but a single compartment 26 or the equivalent portion of two adjoining compartments.

The rotor shaft 50 is axially divided into two end sections 50A and 50B axially spaced from a center portion 50C therebetween. The center section extends axially a distance substantially equal to that of cylindrical shell 22 and is provided at each end with an axial extension in the form of a cylindrical shell 52 fixed to the outer end thereof. Each extension is provided with a pair of diametral slots 54 through which bolts 56 extend to secure annular flange 58 on plate 48 to the shaft 50C. Packing means 62 surrounding shaft members 50A and 50B preclude leakage of high pressure fluid through the annular spaces surrounding the shafts.

The shaft assembly 50A, 50B and 50C is rotatably mounted in bearings 64 supported by independent structure 66, and the entire rotor shaft and integral hood members 44A and 44B are rotated about their central axis by motive means (not shown) acting through a driving gear 68 affixed to the rotor shaft.

In order that the hood members may be adjusted axially to secure an optimum relationship between sealing members 72 and the adjacent face of plates 48, elongate flexible means 74 are directed axially through the rotor shaft and anchored at one end to a plate 76 supported on the end face of shaft 50A, and at the opposite end to a plate 78 within the shaft 50B by eye-bolts 82 or their equivalent. An adjusting bolt 84 secured to plate 78 extends axially through an opening in plate 86 that bears against the end face of shaft 50B in such a manner that tightening the nut 88 against the face of plate 86 tends to shorten the axial distance between plates 76 and 86 and accordingly decrease the axial spacing between hood members 44A and 44B and adjacent end edges of sealing means 72. Conversely, loosening nut 88 permits the fluid pressure within chambers 26 to act against opposing hood members 44A and 44B to force them axially apart so as to increase the axial spacing between sealing means and the confronting surface of the hood members.

While this invention has been described with reference to the embodiment illustrated in the drawing, it is evident that various changes may be made without departing from the spirit of the invention. It is therefore intended that all matter contained in the above description or shown in the accompanying drawings shall be interpreted as illustrative and not in a limiting sense.

We claim:

1. Heat exchanger apparatus or the like comprising in combination a pair of concentric cylindrical drums radially spaced to accommodate an annular heat exchange matrix

therebetween; a housing surrounding both drums arranged to provide a chamber at each end of said matrix having inlet and outlet apertures for a heating fluid and a fluid bearing means for supporting spaced ends of the cylindrical shaft; to be heated being arranged in opposite end walls of said housing axially aligned with the cylindrical drums; flow distributing means in each chamber at opposite ends of the matrix axially aligned to direct fluid flow through a predetermined portion of said matrix, said flow distributing means formed to include an annular opening confronting the axial opening of the adjacent end wall and a sectional opening confronting the end face of said matrix; a telescopic shaft extending freely through the innermost cylindrical drum and the concentric inlet and outlet apertures having independent sections at opposite ends thereof secured to the spaced flow distributing means; means for rotating the cylindrical shaft about its axis; to be heated, the inlet and outlet aperture for the fluid and means adapted to vary the length of said shaft to accordingly vary the clearance space between the flow distributing means and the adjacent face of said annular matrix.

2. Heat exchanger apparatus or the like comprising in combination a pair of concentric cylindrical drums radially spaced to accommodate an annular heat exchange matrix therebetween; a housing surrounding said drums and arranged to provide a chamber at each end of said matrix having inlet and outlet apertures for a heating

4
fluid and a fluid to be heated in the end walls thereof, one pair of said inlet and outlet apertures being arranged at opposite ends of said housing in concentric alignment with the annular drums; flow distributing means in each 5 chamber at opposite ends of said matrix axially aligned and adapted to direct one of said fluids to and through a portion of said matrix therebetween; a telescopically adjustable cylindrical shaft extending freely through the innermost cylindrical drum and its concentrically aligned 10 inlet and outlet apertures, said shaft having spaced ends fixedly secured to the aligned flow distributing means at opposite ends of the matrix; means for supporting the telescopic shaft and the attached flow distributing means; means for imparting a rotary motion to the cylindrical shaft; and tension means extending through the telescopic shaft and secured to spaced ends thereof; and adjusting means at opposite ends of the telescopic shaft 15 adapted to axially vary the clearance space between the flow distributing means and the adjacent face of said 20 annular matrix.

CERTIFICATE OF CORRECTION

Patent No. 3,024,004

March 6, 1962

Charles H. Stoddard et al.

It is hereby certified that error appears in the above numbered patent requiring correction and that the said Letters Patent should read as corrected below.

Column 3, lines 4 and 5, strike out "bearing means for supporting spaced ends of the cylindrical shaft;" and insert instead -- to be heated, the inlet and outlet aperture for the fluid --; lines 18 and 19, strike out "to be heated, the inlet and outlet aperture for the fluid", and insert instead -- bearings means for supporting spaced ends of the cylindrical shaft; --.

Signed and sealed this 9th day of July 1963.
